UNITED STATES PATENT OFFICE.

STEPHEN J. WALLACE, OF LOGANSPORT, INDIANA.

VIOLIN CHIN-REST.

1,387,216.

Specification of Letters Patent. Patented Aug. 9, 1921.

Application filed October 25, 1920. Serial No. 419,363.

To all whom it may concern:

Be it known that I, STEPHEN J. WALLACE, citizen of the United States, residing at Logansport, in the county of Cass and State 5 of Indiana, have invented certain new and useful Improvements in Violin Chin-Rests, of which the following is a specification, reference being had therein to the accompanying drawing.

10 This invention relates to improvements in violin chin rests and the principal object of the invention is to furnish a sanitary chin support having advantages over the ordinary chin rest now in general use.

15 Another object of the invention is to provide an improved chin rest having a pad of soft porous material designed to support the chin in such manner as to prevent irritation, bruising or other injury to the flesh.

20 A still further object of the invention is to furnish a chin rest having a pad which may be readily removed from the main bracket.

With the foregoing objects outlined and 25 with other objects in view, which will appear as the description proceeds, the invention consists in the novel features herein-after described in detail, illustrated in the accompanying drawing and more particularly pointed out in the appended claims.

Referring to the drawing:

Figure 1 is a rear view of the improved chin rest and the clamp which holds the same upon the violin.

35 Fig. 2 is a vertical sectional view of the chin rest showing the same applied to a violin.

Fig. 3 is a rear view of the chin rest with its pad removed.

40 Fig. 4 is a bottom plan view of the improved pad.

Fig. 5 is a perspective sectional view of a portion of the pad.

In the drawing, 1 designates a clamp of 45 known construction used in securing the legs 2 of the chin rest to a violin V.

The chin rest includes a substantially elliptical-shaped plate 3 which is secured to the legs 2 and is provided with apertures 50 4 for a purpose hereinafter described.

5 designates the improved chin supporting pad which in the present instance consists of a thick rubber base 6 and a sponge rubber body 7. The base 6 is provided with a pocket 55 8 opening from one edge of the base and

the plate 3 is designed to be inserted in this pocket for holding the pad in place. If desired screws may be passed through the base and through the apertures 4 of the plate 3 for locking the pad securely in position. 60

The body 7 is provided with a depression 9 designed to be engaged by the chin of the violinist. By constructing the body 7 of sponge rubber I provide a soft pad which fits snugly under the chin of the player and 65 by reason of its porosity allows air to circulate under the operator's chin and through the pad. The pad being made entirely of rubber may be washed or otherwise cleaned and thus it may be maintained in sanitary 70 condition.

From the foregoing I believe the construction and advantages of my improved chin rest will be readily apparent to those skilled in the art, and I am aware that various changes and modifications may be made in the construction shown without departing from the spirit of the invention as set forth in the claims. 75

What I claim and desire to secure by Letters-Patent is:

1. A violin chin rest including a supporting plate, a pad resting on said plate and having a base formed of thick resilient material provided with a pocket designed to 85 engage said plate, and a soft porous body resting on said base.

2. A violin chin rest including a substantially elliptical pad having a base provided with a pocket opening from one edge of the 90 same and designed to receive a supporting element, and a body secured to said base, formed of sponge rubber and having a depression in its upper surface designed to receive the violinist's chin. 95

3. A violin chin rest including a substantially elliptical apertured plate, a pad engaging said plate and provided with a base having a pocket in which said plate is inserted, and a body included in said pad and 100 formed of sponge rubber.

4. A violin chin rest of the kind defined by claim 3 in which the plate is apertured to receive fastening means.

In testimony whereof I hereunto affix my 105 signature in the presence of two witnesses.

STEPHEN J. WALLACE. [L.S.]
